UNITED STATES PATENT OFFICE.

TOBIAS KAPPELER, OF CAMBRIDGE, MASSACHUSETTS.

DESIGN FOR BAS-RELIEF.

Specification forming part of Design No. 7,535, dated July 14, 1874; application filed June 22, 1874.
[Term of Patent 3½ years.]

To all whom it may concern:

Be it known that I, TOBIAS KAPPELER, of Cambridge, Massachusetts, have invented a new and original Design in Bas-Relief of the late Prof. Louis Agassiz, as fully represented in the accompanying photographic illustration, to which reference is made.

The nature of my design consists in a profile bas-relief mounted upon a background of dark-colored velvet, or other suitable material, as usually employed for similar purposes.

This bas-relief I construct of plaster-of-paris,

or similar composition; or the same design may be cast of metal, or struck up from thin sheet metal, and then silver-plated.

What I claim as my invention is—

The design for a bas-relief profile of Prof. Louis Agassiz, as shown by the accompanying illustration of the same.

TOBIAS KAPPELER.
